ABSTRACT OF THE DISCLOSURE

A hydraulic system having calibration, bandwidth, and dash pot controls with indicators for each, and a dash pot adjustment.

BACKGROUND OF THE INVENTION

This invention relates to hydraulic systems and, more particularly, to valve positioners or the like.

In the past, it has been the practice to calibrate a valve positioner by adjusting the position of a threaded shaft to vary the tension of a feedback spring. Such a device is disclosed in U.S. Pat. No. 3,101,031. Such devices are inaccurate and have no visual indication of calibration.

Bandwidth adjustments are also old in the art; however, these have required clumsy adjustment procedures. Further, no bandwidth indicators have been provided with a correction which is a function of stroke length.

It is also old in the art to provide negative feedback to a valve positioner and to adjust the feedback rate. However, such devices are complicated and have no visual indication of feedback rate.

SUMMARY OF THE INVENTION

In accordance with the devices of the present invention, the above-described and other disadvantages of the prior art are overcome by providing a movable suspension system for the feedback spring. The set point may, thus, be adjusted accurately.

In accordance with a feature of the invention, a visual indication of the set point adjustment is provided.

According to another feature of the invention, a bandwidth adjustment is provided including a lead screw and a nut therefore to operate a feedback lever.

Still another feature of the invention includes a bandwidth indicator scale having a lined connecting plate extending from the nut to the scale. The plate may, thus, be adjusted to make the scale read accurately for a particular length of stroke.

A further feature of the invention resides in the use, for example, a pneumatic bellows or feedback. The output of the bellows operates a diaphragm. The diaphragm chamber is vented through a needle valve which carries a scale to indicate the reset adjustments.

The above-described and other advantages of the invention will be better understood from the following description when considered in connection with the accompanying drawings.

BRIEF DESCRIPTION OF THE DRAWINGS

In the drawings, which are to be regarded as merely illustrative:

FIG. 1 is a vertical sectional view of a hydraulic control system constructed in accordance with the present invention;

FIG. 2 is a top plan view of a needle valve assembly shown in FIG. 1.

FIG. 3 is a perspective view, partially exploded, of a portion of the set point indicator of the present invention;

FIG. 4 is a side elevational view of a portion of the bandwidth adjustment and indicator of the present invention;

2

FIG. 5 is a top plan view of the structure shown in FIG. 4;

FIG. 6 is a sectional view taken on the line 6—6 of a set screw adjustment shown in FIG. 5;

5 FIG. 7 is an enlarged broken away front elevational view of the bandwidth adjustment and index marker therefor;

FIG. 8 is a top plan view of the structure shown in FIG. 7; and

10 FIG. 9 is a vertical sectional view taken on the line 9—9 of the structure shown in FIG. 8.

DESCRIPTION OF THE PREFERRED EMBODIMENT

15 In FIG. 1, a valve positioner is indicated at 10. The valve to be positioned is indicated at 11 in a housing 12. Housing 12 includes a valve seat 13. Valve 11 is fixed to a piston rod 14. A piston 15 is fixed to rod 14. Cylinder 16 surrounds pistons 15. Piston 15 has a groove 17 in which an O-ring 18 is positioned. O-ring 18 seals the space between piston 15 and cylinder 16. Piston 15 is moved upwardly by fluid pressure supplied by a pump 19 which is operated by an electric motor 20. The pressure below piston 15 is determined by a hydraulic amplifier 21 which receives an input from pump 19 through a conduit 22. The lower end of cylinder 16 is supplied with fluid under pressure by pump 19 through a conduit 23. Amplifier 21 has outlet conduit 24 with an orifice 25. Hydraulic fluid is bled from orifice 25 at a rate determined by the position of vane 26. Vane 26 is fixed to a beam 27. When amplifier 21 causes the pressure in conduit 23 to drop by bleeding sufficient hydraulic fluid through orifice 25, a spring 28 closes valve 11.

A body 29 encloses rod 14 and a follower 30 for spring 28, follower 30 being fixed to rod 14. Housing 29 is joined to an intermediate body portion 31 of positioner 10 at 32 and 33.

Positioner 10 has a body portion or end cover 34 and a body portion or side cover 35.

40 A divider and beam support 36 extends across body 31 near the upper end thereof. All of the structures shown in FIG. 1 below divider 36 may be entirely conventional. These devices may also operate in a conventional way, for example, as shown and described in U.S. Pat. No.

45 3,087,471. Thus valve 11 in this application corresponds to valve 10 in FIG. 5 in the patent. Conduit 23 in this application corresponds to conduit 17 in the patent. Piston 15 is the same in both. In the patent, a pump is indicated at 25, and a hydraulic amplifier is indicated between conduits 20 and 63.

50 In this application, in end cap 34, a control mechanism 37 is shown including an arm 3 pivoted on a shaft 39 by a ball bearing 40 carried thereby to rest on the upper end of piston rod 14. Arm 38 has a leading screw 41 threaded therethrough. Lead screw 41 may be turned to move a nut 42. Nut 42 has a projection 43 on which another arm 44 rests. Arm 44 is rotatable about a fixed shaft 45. An index marker 46 is also fixed to nut 42. A spring 47 is fixed to the left end of beam 27. The upper end of spring 47 is supported by a flexible strand 48.

55 Strand 48 is movable over a pulley 49 with a nut 50. Nut 50 is moved by turning a lead screw 51 carried by arm 44. Lead screw 51 is threaded through an index marker 52.

60 Beam 27 is supported by flexure strips 53 and 54. A coil 55 is fixed to the right end of beam 27. The entire construction of the positioner 10 is made of non-magnetic materials with the exception of a body 56. Body 56 is made of a magnetic material.

65 A bellows 57 is located between arm 44 and a fixed projection 58. Bellows 57 has an output conduit 59 which extends into a chamber 60. Chamber 60 is enclosed with

a diaphragm 61. Diaphragm 61 is connected to beam 27 by a fixed member 62. Chamber 60 has an outlet conduit 63 in which a needle valve 64 is disposed.

In the operation of positioner 10 shown in FIG. 1, the input is supplied electrically on leads 65 and 66 connected to coil 55. Piston 15 will then assume a position in accordance with the signal applied to leads 65 and 66. Should there be any variation in the system so that piston 15 assumes a position error, this will be reflected in a change in the position of beam 27. This is true because the position of piston 15 and, therefore, piston rod 14 will cause arm 38 to move up or down by engagement of ball 40 with the upper end of rod 14. This, in turn, will cause arm 44 to move because arm 44 rests on projection 43 of nut 42. Movement of arm 44 will then cause the spring 47 to supply more or less force to the left end of beam 27. The force supplied by spring 47 is, thus, balanced against the force supplied by coil 55 in its attraction for body 56. Note will be taken that when beam 27 tilts in a counterclockwise direction, orifice 25 is closed by vane 26; and the pressure in conduit 23 is increased. Tilting of beam 27 in a clockwise direction produces the opposite effect.

In accordance with the present invention, downward movement of arm 44 from the position shown causes bellows 57 to collapse. Downward movement of arm 44 is, therefore, retarded because air is not allowed to escape from bellows 57 except at a lower rate controlled by needle valve 64. Still further, negative feedback is provided in that the increased pressure in chamber 60 causes a counterclockwise movement on beam 27 through member 62.

It is a feature of the invention that bellows 57 is provided with chamber 60 for the negative feedback to provide damping. It is also a feature of the invention that needle valve 64 is provided to provide for the damping, yet insures final accurate correction.

Another feature of the invention resides in the use of indicia 64' and an index marker 64" relative to needle valve 64 to indicate the reset action adjustment of needle valve 64.

An adjustment card 67 is fixed to arm 38 by a screw 68. Card 67 has a slot 69 therethrough. Screw 68 extends through slot 69. The position of card 67 may be adjusted along the length of arm 38 by loosening screw 68 and moving card 67 beneath screw 68. An index marker is provided on card 67 at 70. Arm 38 has an indicia 71 thereon positioned so that index marker 70 may be located relative thereto in a position corresponding to the stroke of valve 11 desired for a particular input signal on leads 65 and 66. In this position, by comparing marker 46 with indicia at 72 and 73, the percentage of proportional bandwidth may be read from indicia 73 on card 74 fixed to arm 38. The proportional bandwidth relates the range of input signal on leads 65 and 66 to the range thereon at a particular stroke setting.

Arm 44 has card 75 fixed thereto with indicia 76. Comparison of marker 52 with indicia 76 gives the set point of the positioner 10.

An airtight O-ring seal 34' keeps valve 64 and all the structures in end cap 34 dirt free.

From the foregoing, it will be appreciated that, by the use of lead screw 51, it is possible to adjust the set point accurately. Further, indicia 76 provide a visual indication of the set point adjustment. A bandwidth adjustment is also provided including lead screw 41. Percentage of bandwidth is indicated by indicia 73 for any given stroke setting of card 67. The arrangement of bellows 57 with diaphragm 61 provides for negative feedback. Damping is simultaneously provided by bleeding air from bellows 17 through needle valve 74. The reset action is visible through indicia 64'.

In FIG. 3, an ear 76 is fixed to arm 44 as is card 75 and a shaft 77. Shaft 77 has a flange 78 fixed thereto which holds pulley 49 on shaft 77.

Nut 50 has an area 79 to which strand 48 is fixed, strand 48 and lead screw 51 being omitted in FIG. 3 for clarity. Index marker 52 is fixed to a nut 80 which is exposed out of position for clarity. As shown, nuts 50 and 80 have vertical surfaces 81 and 82, respectively, which fit contiguous to a vertical surface 83 of arm 44.

An enlarged view of cards 67 and 74 is shown in FIG. 4 with card slot 69, set screw 68 and arm 38 with indicia 71 on a card 84 fixed to arm 38. A slot 85 extends all the way through arm 38. Lead screw 41 has been omitted for clarity. A top plan view of the structure of FIG. 4 is shown in FIG. 5.

The manner in which set screw 68 fits through slot 69 and is threaded to card 74 and clamps card 67 in a fixed position relative thereto is illustrated in FIG. 6.

FIGS. 7 and 8 illustrate how index marker 46 slides between arms 38 and 44 if lead screw 41 is turned. As stated previously, index marker 46 is fixed to traveling nut 42. Projection 43 includes a shaft 86 fixed to nut 42 and a ball bearing 87 pressed onto shaft 86.

As shown in FIG. 9, if desired, index marker 46 may be fixed both to shaft 86 and to nut 42.

What is claimed is:

1. In a control system, a set point adjustment comprising: a support; a first member; a first arrangement movably mounting said first member on said support in a manner such that at least one portion thereof is movable between first and second positions over a path of travel; first means mounted on said support and connected to said first member, said first means being actuatable to move said first member toward said first position along said path of travel thereof; a second member; a second arrangement movably mounting said second member on said support in a manner such that at least one portion thereof is movable between first and second positions over a path of travel closer to and farther away from said first member, respectively, said second member being connected to said first means in a manner to deactivate said first means when said second member moves toward said first member, said first member being farther from said second member in said first member first position than in said first member second position; a tension spring having one end connected to the said portion of one of said members; second means mounting the other end of said spring on the said portion of the other of said members, said second means including a flexible strand having one end fixed to the other end of said spring; a pulley; a third arrangement rotatably supporting said pulley on said other member, said strand being threaded around said pulley; and third means connected between said other member and the other end of said strand and adjustable lengthwise therebetween to adjust the amount of tensile stress on said spring.

2. The invention as defined in claim 1, wherein said third means includes a lead screw, means to hold said lead screw in a rotatable but otherwise fixed position relative to said other member, a nut threaded onto said screw fixed to said strand, an index marker threaded onto said screw, said nut and said marker being constructed and positioned to move axially on said screw when said screw is rotated, and a scale fixed to said other member in a position adjacent said marker to indicate the set point by the position of said marker relative thereto.

3. In a control system, the combination comprising: a support; a first member movably mounted on said support; a second member movably mounted on said support; a third member movably mounted on said support, said first member being mounted on said support in a position in engagement with said third member to be moved when said third member is moved; first means mounted on said support connected to said third member, said first means being responsive to hydraulic pressure to move said third member; a hydraulic pump mounted on said support; an inlet conduit connected from said pump to said first means to supply fluid under pressure thereto; a hydraulic ampli-

fier mounted on said support having an inlet and an outlet, said amplifier having a valve to decrease the opening of said inlet as the pressure between said inlet and said outlet increases, and vice versa; a conduit connected from said inlet conduit to said amplifier inlet providing free and open communication of hydraulic fluid therebetween; a bleed conduit connected from said amplifier outlet having a bleed orifice therethrough; a balance beam having a flapper valve fixed thereto to vary the opening of said orifice; second means to pivot said beam from said support near the center of said beam; a projection adjustably mounted on said first member; a tension spring connected from said second member to one end of said beam in a position to bias said second member into engagement with said projection and accordingly to bias said first member into engagement with said third member, said spring also tending to pivot said one beam end toward said second member; electromagnet means mounted on said support and the other end of said beam to provide a variable force on said beam tending to place a tensile stress on said movement of said one beam end toward said second member causing said flapper valve to open wider, and vice versa, adjustment of the position of said projection on said first member causing movement of said second member relative to said first and third members when said first and third members are held stationary; an index marker mounted on said first member; first and second cards fixed to said first member, said second card having indicia thereon to indicate bandwidth; a third card movably mounted relative to said first and second cards, said third card having indicia thereon extending from said index marker to said second card indicia, one of said first and third cards having indicia thereon adjacent the other to indicate the stroke setting of said third card; and third means adjustably mounted relative to said first member to hold said third card releasably in a fixed position.

4. The invention as defined in claim 3, including a lead screw mounted in a rotatable angular but otherwise fixed position relative to said first member, a nut threaded onto said lead screw, said nut being positioned in a manner such that it will not rotate relative to said first member, said index marker being fixed to said nut, said projection also being fixed to said nut.

5. The invention as defined in claim 4, wherein said first and second members are movable up and down generally in parallel planes, said index marker being slidable between said first and second members contiguous to each,

said third card having a slot therethrough, said third means including a set screw extending through said slot and being threaded into said second card.

6. The invention as defined in claim 1, wherein said first means includes a cylinder fixed relative to said support, a piston rod slidable longitudinally in said cylinder, a piston fixed to said rod in a position sealing against said cylinder, a linkage connected between said piston rod and said first member, a hydraulic pump, an inlet conduit connected from said pump to said cylinder, a hydraulic amplifier mounted on said support having an inlet and an outlet, said amplifier having a valve to decrease the opening of said inlet as the pressure between said inlet and said outlet increases, and vice versa, a conduit connected from said inlet conduit to said amplifier inlet providing free and open communication of hydraulic fluid therebetween, a bleed conduit connected from said amplifier outlet having a bleed orifice therethrough, a balance beam having a flapper valve fixed thereto to vary the opening of said orifice, second means to pivot said beam from said support near the center of said beam, said second member including a longitudinal extension integral with said balance beam at one end thereof.

7. The invention as defined in claim 6, wherein said third means includes a lead screw, means to hold said lead screw in a rotatable but otherwise fixed position relative to said other member, a nut threaded onto said screw fixed to said strand, an index marker threaded onto said screw, said nut and said marker being constructed and positioned to move axially on said screw when said screw is rotated, and a scale fixed to said other member in a position adjacent said marker to indicate the set point by the position of said marker relative thereto.
